UNITED STATES PATENT OFFICE.

WALTER P. MURPHY, OF CHICAGO, ILLINOIS.

RELEASE-RIGGING.

1,031,811.

Specification of Letters Patent.

Patented July 9, 1912.

Application filed January 14, 1911. Serial No. 602,665.

To all whom it may concern:

Be it known that I, WALTER P. MURPHY, a citizen of the United States, residing at Chicago, in the county of Cook and State of Illinois, have invented certain new and useful Improvements in Release-Rigging, of which the following is a specification.

This invention, while adapted to be used with various types of release rigging, is more especially adapted for use in connection with the release rigging shown in the patent to J. R. Carmer, No. 799,446, dated September 12, 1905 and for purposes of illustrating the invention, I have adopted the Carmer levers.

In operating release rigging, especially of the two-lever type, considerable force is exerted upon the pin operating lever, which sometimes results in the pin lever breaking at a point between its fulcrum and the locking pin of the coupler, thus freeing the pin lever of its weight, whereupon it is free to fly back and strike the operator.

The object of my invention is to eliminate the liability of the operator being struck by the pin lever, by introducing means in the rigging to limit the upward and backward movement of the pin lever; and with this and minor objects in view, my invention consists of the parts and combination of the parts as will be hereinafter more fully pointed out.

In the drawing, Figure 1 is a top plan view of the end of a car, with parts broken away, with a release rigging embodying my invention attached to the end sill of the car; Fig. 2 is an enlarged detail view of the hand and pin levers broken away with their fulcrum and my improved stop; Fig. 3 is a vertical section longitudinally of the fulcrum, with associated parts shown in Fig. 2; and Figs. 4 and 5 are detail views of the casting and stop, respectively.

The numeral 1 represents a car broken away, 2 the end sill of the car, 3 the coupler head and 4 the locking pin.

The fulcrum according to my invention, consists of a base 5, provided with openings at each end through which rivets 6 extend, whereby the base may be secured to the end sill. Extending from said base is a hollow fulcrum member 7 having a reduced fulcrum bearing 8 terminating in an octagonal end or extension 9. This extension may be of any rectangular shape but I prefer to make it octagonal so as to provide

for a practically wide range of adjustment of the stop (to be hereinafter referred to).

The numeral 10 represents a hand operated lever, which is loosely mounted near one end on the bearing 8. It will be noted from Fig. 3 that the opening 11 in the lever is of greater diameter than the bearing 8, whereby the lever has a loose bearing or pivot on said bearing. This lever, as stated projects beyond the fulcrum bearing 8 and has at one end, an upwardly extending hook shaped protuberance 12, upon which rests the pin operating lever 13, which is also provided with an opening 14 larger than the pivot or fulcrum bearing, whereby it, like the lever 10, has a loose pivot bearing. The inner end of the pin lever is deflected as shown in Fig. 1 and provided with a reduced portion adapted to pass through the eye of the locking pin 4, the extreme inner end of the lever being bent to form a hook to prevent accidental disengagement of the lever from the locking pin. The outer end of the hand operated lever 10 sags downwardly to a point below the end sill 2, as shown in dotted lines, Fig. 1. The sagging end of the hand operated lever is arranged in such relation with respect to the end sill of a car or the corner step of a car to enable the operation of the same through the medium of the foot of the train-man, so that the train-man can use his lantern while uncoupling or immediately after the uncoupling operation.

The safety stop comprises a washer 15 provided with an octagonal depression or recess 16 in its under face, adapted to fit over the octagonal end of the fulcrum member 7 as clearly shown in Figs. 2 and 3.

The numeral 17 represents a bolt passing through the end sill, the base plate 5, the fulcrum member 7, and the washer 15, and provided with a nut 18, whereby the washer is securely clamped on the end 16 of the fulcrum member. As an additional safe guard to prevent the nut 18 from becoming loosened, I provide a cotter pin 19, which passes through the bolt.

Projecting upwardly from the washer 15 is an arm 20 provided with a strengthening rib 21, said arm being provided with a stop 22, over which the strengthening rib 21 projects. The stop 22, as shown in Fig. 3, projects over the pin operating lever 13 in the path of its upward and backward movement. It will be noted from Fig. 2, that the

arm 20 and its stop 22 are deflected forward of the center of the washer 15.

The octagonal bearing of the washer permits of placing the arm 21 with its stop 22, 5 in various angles without changing the relative position of the washer with reference to the levers. The washer, while serving as a lock for the stop, also serves to keep the levers 10 and 13 on the bearing of the ful- 10 erum.

As above stated, the pin operating lever, at times, breaks under stress and the usual point of fracture is indicated by α , on Fig. 1. When the fracture happens, the pin lever, in the constructions heretofore used, is freed from all restraint or weight and under the influence of the hand operated lever 10 flies upward and back toward the side of the car, which results in an injury to 20 the operator. By my invention, all liability of injury to the operator, due to fractures of the pin lever is entirely obviated inasmuch as the stop 22 limits the upward and 25 backward movement of the pin lever so that in the event of a fracture of the character above referred to, the lever is stopped in its upward and backward movement by the stop 22.

The portion of the fulcrum member be- 20 tween the base 5 and the bearing 8, serves as a spacing member to space the levers from the end sill of the car, thus reducing the liability of the levers hanging by reason of accidental engagement with the end sill,

as will be understood by those skilled in the 35 art.

What I claim is:—

1. A fulcrum for a release rigging comprising a bearing for the levers of the rig- 40 ging, a projection having flat sides extending axially from the bearing, a washer having a seat fitting over said projection, and a stop projecting from said washer and extending into the path of the pin lever to prevent an excess upward movement of the 45 said lever.

2. A fulcrum for a release rigging comprising a base constructed to be secured to a car, a hollow fulcrum bearing for the levers of the rigging, a hollow spacing mem- 50 ber integral with and supporting the said bearing from said base, a hollow octagon shaped projection extending axially from the outer end of said bearing, a washer having an octagonal recess to fit over said pro- 55 jection, a stop projecting from said washer and extending over the pin lever to limit its upward movement and a bolt passing through the base, spacing member projection and washer, whereby the washer and 60 stop are maintained in the desired position.

In testimony whereof I affix my signature in presence of two witnesses.

WALTER P. MURPHY.
